UNITED STATES PATENT OFFICE.

CHARLES S. WINN AND CLARENCE A. WALL, OF ROCKFORD, ILLINOIS.

ROOF-SCAFFOLD BRACKET.

1,152,685.

Specification of Letters Patent.

Patented Sept. 7, 1915.

Application filed July 27, 1914. Serial No. 853,444.

To all whom it may concern:

Be it known that we, CHARLES S. WINN and CLARENCE A. WALL, citizens of the United States, residing at Rockford, in the county of Winnebago and State of Illinois, have invented certain new and useful Improvements in Roof-Scaffold Brackets, of which the following is a specification.

This invention relates in general to roof scaffolds and more particularly to brackets adapted to support a scaffold or staging such as is used when shingling, repairing or doing other work upon an inclined roof.

One of the primary objects of our invention is to provide a bracket of this character, simple in its design and structure so that it will be light in weight and inexpensive to manufacture, and which will be capable of various adjustments to permit its use on roofs of many different styles and pitches.

Another object of our invention is to provide a novel means for maintaining the bracket in its operative position and for permitting it to be readily adjusted to different elevations upon the roof.

A further object is to provide means for connecting the bracket supporting means to the side of a gable roof opposite to that on which it is located, this being desirable when the ridge-boards are not yet placed in position and when working on hip-roofs.

A further object is to construct a bracket of two triangular sections pivotally connected at one angle corner and with one section arranged within the other and so proportioned that when the outer section rests upon a roof of a relatively steep incline with its pivoted angle corner highest upon the roof, the entire inner section when adjusted to a horizontal position will be disposed directly above and in vertical alinement with the lower section, so as to prevent tipping of the bracket out of its operative position.

Referring to the drawings: Figure 1 is a view in perspective of one of our improved scaffold brackets, showing it mounted upon a gable-roof. Fig. 2 is a view in perspective of the bracket in folded or collapsed position in which it occupies but little space and may be conveniently transported or stored. Fig. 3 is a plan view showing a pair of our improved brackets supporting a scaffold or staging upon a gable-roof and being connected to the roof in the manner shown in Fig. 1. Fig. 4 is an end view of a gable-roof showing another manner of supporting

the scaffold brackets, and Fig. 5 is a view in perspective of the supporting means shown in Fig. 4.

Roof brackets of the general character to which our invention pertains are generally used in pairs to support a scaffold or staging upon an inclined roof, the brackets being located at opposite ends of the staging.

Brackets embodying our invention are all similar in structure and each has separate means for maintaining it in operative position and for adjusting it to different elevations upon the roof. Each bracket is formed of two metal lengths bent into triangular shaped sections 6 and 7 whose ends terminate at one angle of the triangles and are connected by a bolt 8 passing therethrough so as to pivotally connect the triangular sections and permit relative movement thereof. Section 7 forms a base and is adapted to be positioned with its pivot end highest upon an inclined roof, so that the section 6 may be swung to a horizontal position to receive a staging or scaffold 9 upon its top face. The section 6 is arranged within the section 7 so as to be movable into the same plane thereof and is shorter in length from its pivot than section 7, as is clearly shown in Fig. 2, this difference in length of the sections permitting, when the bracket is mounted on a roof of a maximum incline, the outer end of section 6 to be maintained substantially in vertical alinement with the outer end of section 7 thereby insuring against overbalancing of the bracket. Braces 11 pivoted at one end to opposite sides of section 7 have their outer ends adjustably connected to the corresponding side portions of section 6 for supporting the same in a scaffold carrying position. The braces are connected with the section 6 by means of bolts 12 adapted to be inserted through the requisite holes 13 in the braces, which will position the outer end of the section 6 at the proper height.

The bracket is supported and maintained in position by a chain or cable attached to an upper portion of the roof. The supporting connection includes a member carried by the bracket, to which means one end of the chain or cable is permanently attached and to which the cable may be attached at different points intermediate its ends to permit ready adjustment of the bracket to different elevations on the roof. The member as shown is bent upon itself to form a piv-

otal connection with bolt 8 intermediate the ends of sections 6, one end of said member having an eye 14 with which one end of the chain 15 is attached and the other end of said member being formed in an upstanding hook 16. The chain 15 has a hook 17 at its other end adapted to be engaged with the roof, in practice the engagement being either with a ridge-board 18 as shown in Fig. 1 or by engaging the hook with a roof board (not shown) before the roof is shingled.

The chain supports for the brackets are of such length that when the hooks 17 are engaged with a ridge-board the brackets are maintained at a relatively low position on an ordinary roof. When in shingling or repairing a roof it becomes desirable to move the brackets successively to higher elevations on the roof, the brackets are moved upward and maintained in their new positions by engaging the chain portions which are adjacent the brackets with the hooks 16 thereof, in the manner shown in Figs. 1 and 3, thus permitting the brackets to be readily positioned at any intermediate elevation on the roof within the limits of the chain lengths 15.

When shingling a roof it is customary not to mount the ridge-boards in position until the shingling has been completed, therefore a different means for connecting the brackets with the roof is necessary. Such a means we have shown in Fig. 5 and illustrated its application in Fig. 4. This means comprises a separate chain or cable length 19 having an ordinary hook 20 at one end adapted to be engaged with the chain section 15, and a peculiarly shaped hook 21 at its opposite end, which hook has a relatively wide mouth and holding face preferably formed by bending a suitably shaped strip of sheet metal upon itself. This wide-faced hook is adapted to engage a shingle in an effective manner and without injury thereto. The hook is illustrated in the drawings in Fig. 4 as engaged with a shingle for the purpose of sustaining the bracket in position on the opposite side of the roof.

It will be manifest that the brackets when connected to the roof through means of the auxiliary chain lengths may be adjusted to different elevations in a manner similar to that above described. Also when the chain lengths 15 are not long enough for a particular roof, the hooks 17 of said chains may be hooked into chains 19 adjacent the hooks 21, and the hooks 20 of the latter chains en-

gaged with the roof, thus permitting the staging to be positioned at the lower portion of the roof. When working on hip-roofs it will be obvious that the scaffold brackets cannot be maintained in position as in the manner of an ordinary gable roof; and under this condition the auxiliary chains 19 would be attached to chains 15, and the chains extended around the sides of the roof to the side opposite to that upon which the brackets are positioned and then engaged with the shingles or with the roof boards of said opposite side.

It will be seen that with the provision of scaffold brackets having roof connecting means of the above described character, the brackets may be practically used on various types of inclined roofs and be easily adjusted to any desired position to meet the different conditions which arise in roof building and repairing.

The brackets are designed with the view of being collapsible so as to displace but a minimum of space when being shipped or transported, this feature being clearly shown in Fig. 2.

We claim as our invention:

1. A roof scaffold bracket comprising a pair of triangularly shaped sections arranged one within the other and having their ends terminating at a common apex, a bolt passing through said ends whereby the sections are pivotally connected, means for holding the outer ends of the sections spaced apart, and roof-connecting means connected with the pivoted ends of the sections for holding the bracket at different elevations on the roof.

2. A roof scaffold bracket comprising a pair of triangularly shaped sections each formed of a single strip of metal, one of the sections being disposed within the other, means pivotally connecting the sections at a common apex whereby the sections may be collapsed and moved relatively so that the outer ends of the sections may be spaced apart, adjustable means for holding the outer ends of the sections spaced apart various distances, and roof-connecting means connected with the pivoted ends of the sections for holding the bracket at different elevations on a roof.
